UNITED STATES PATENT OFFICE.

HERBERT G. PECK, OF BLOOMFIELD, NEW JERSEY.

GAGE.

1,357,589.

Specification of Letters Patent. Patented Nov. 2, 1920.

Application filed March 14, 1919. Serial No. 282,538.

To all whom it may concern:

Be it known that I, HERBERT G. PECK, a citizen of the United States, and resident of Bloomfield, in the county of Essex and 5 State of New Jersey, have invented certain new and useful Improvements in Gages, of which the following is a specification.

My invention relates to improvements in measuring instruments, such as gages, particularly to the class adapted to measure 10 the distances between threads, recesses and the like upon rods, taps, bolts and the like, and has for its object to provide a gage comprising a suitable support having adjustable pins or the like for spacing according 15 to the threads, etc. upon the articles to be gaged, with means to regulate the space between said pins according to the requirements, and for maintaining the elements of 20 the gage in inset relation.

My invention comprises novel details of improvement that will be more fully hereinafter set forth and then pointed out in the claims.

Reference is to be had to the accompanying drawings, forming part hereof, in which—

Figure 1 is a plan view of a gage embodying my invention;

Fig. 2 is a side view, partly in section on the line 2—2 of Fig. 1;

Fig. 3 is a cross section on the line 3—3 in Fig. 1;

Fig. 4 is a plan view of a modification;

Fig. 5 is a side view of Fig. 4;

Figs. 6 and 7 are respectively cross sections on lines 6—6 and 7—7 in Fig. 5; and

Fig. 8 is an end view of Fig. 5 partly in section.

Similar numerals of reference indicate corresponding parts in the several views.

The numeral 1 indicates a support shown in elongated form adapted to support members 2 and blocks 3. In Figs. 1, 2 and 3 45 said support is shown in the form of a frame having a longitudinal space 4 opening through the top and bottom thereof and closed at the opposite ends adapted to receive portions of members 2 and blocks 3.

The members 2 are shown as having relatively narrow portions 2^a to fit within the space 4 and widened lowered portions provided with recesses 2^b shown in V-like form adapted to receive and fit upon an article to 55 be gaged such as a screw, tap, bolt or the like. The members 2 are shown provided

with shoulders 2^c (Fig. 3) to fit against the opposing surfaces of the side bars of support 1 whereby the V-like recesses 2^b of several members 2 may be set and maintained in the same plane for the purpose of maintaining the gage in proper position upon the article 5 to be gaged. The blocks 3 are provided with longitudinal holes 3^a (Fig. 2) adapted to receive pins 6 or the like 6 which are provided with tapering or sharpened ends 6^a adapted to fit in the threads 5^a of the article to be gaged. At 7 are gage blocks adapted to fit adjustably in space 4 of support 1 between spaced blocks 3 and members 2, as well as between pin blocks 3 for the purpose of maintaining said members and blocks in spaced relation gaged according to the measurement required. The blocks 7 are of any desired width so as to be interchanged between member 2 and block 3, or between the blocks 3. At 8 is a screw threaded in a block-like end portion 1^b of support 1 and adapted to be pressed against a block 3 to maintain all of said blocks, members 2 and gage blocks 7 in secure set relation in the support.

In Figs. 4 to 8 the support is shown in the form of rods 1^a shown spaced apart 85 upon a pin block 3 and block 1^b, in which block 1^b the screw 8 is threaded. Said blocks 3 and 1^b have holes provided with means to receive rods 1^a whereby the latter are spaced apart to receive in the space 4 therebetween the appropriate portions of 90 one or more members 2, pin blocks 3 and gaging blocks 7. Said pin blocks and block 1^b are shown secured to rods 1^a by means of screws 9, whereby said blocks may be set 95 along rods 1^a in desired spaced relation and said rods and blocks will be securely united. One of the members 2 is shown provided with holes 2^c whereby the latter is adjustably maintained upon rods 1^a while any 100 desired number of other members 2 may have narrowed portions 2^a to adjustably fit between said rods. The latter member or members may have shoulders 2^d (Fig. 6) whereby the V-like recess 2^b of such member 105 or members may be maintained set in the same plane with the other member or members for centering the members upon an article 5. The pin blocks 3 fit in space 4 between rods 1^a and may be provided with 110 plungers or shoulders 3^a, Fig. 7, to fit against said rods for locating said blocks in

desired position. It will be understood that any desired number of V-like members 2 and pin blocks 3 may be provided upon the rods 1^a, and that any desired number 5 of gage blocks 7 may be interposed between one or more members 2 and blocks 3 for determining the distance between spaced pins 6 according to the measurement to be made and that screw 8 will secure all of 10 said members together as previously described.

One or more of the blocks 3 may carry one or more pins, the block at the left hand side of Fig. 5 being shown provided with 15 two pins 6.

While the tapering ends of pins 6 are shown entered in the threads 5^a it will be understood that one of the pins 6 may be set at 5^b (Fig. 2) in the space at the shank of 20 the article 5 or at the beginning of the threads thereon to measure therefrom by means of one or more other pins 6.

In accordance with my improvements, when it is desired to measure distances between threads, recesses, teeth and the like upon an article 5, such as a rod, tap, bolt, screw or the like, the pin blocks 3 will be adjusted along the support to the positions required to enter the tapering ends of the 30 corresponding pins in the threads, recesses or the like, and gage blocks 7 of required dimensions will be interposed between said blocks or members, and then the screw 8 may be tightened against one of the blocks 35 or members to retain said parts all in secure position. Since the thickness of the gage blocks will be known as well as the distance from the axis of pin 6 to the side of block 3, the spacing of the threads, recesses or the 40 like made or being made upon the article 5 may be determined. If it be desired to have pins 6 maintained in definite spaced gaged relation upon support 1 as a standard, whereby to measure or gage articles having 45 threads, recesses or the like, the members 2 and blocks 3 with the required interposed gage blocks 7 may be assembled and maintained set, whereby the appropriate pins 6 may be placed upon the threads, recesses 50 or the like as the work progresses.

The V-like recesses in spaced members 2 are maintained on a plane so that when adjusted upon the article to be gaged all the members of the gage will be alined along 55 the article and maintained in parallelism in all directions with respect to the article, by pressing the latter into such recesses. Any desired number of members 2 may be provided in spaced relation on the support 60 with relation to the pin blocks 3.

My invention is simple and cheap to manufacture, may be readily operated, and is most accurate in the use of gage blocks, such as those commonly called "Johansson" 65 gages, when used as standards.

While I have illustrated and described a specific embodiment of my invention, it will be understood that changes may be made in the arrangement set forth without departing from the spirit of my invention. 70

Having thus described my invention, what I claim and desire to secure by Letters Patent is:—

1. A measuring instrument comprising a support, members carried thereby having 75 means for coöperation with an article to be gaged for positioning the members, blocks having adjustable pins to coöperate with said article, and means to maintain said blocks in spaced measured relation in said 80 support.

2. A measuring instrument comprising a support, members having means for coöperation with an article to be gaged for positioning the members, blocks having adjustable pins to coöperate with said article, and gage blocks adapted to be interposed 85 between said pins, and means to maintain said members and blocks in spaced gaged relation for coöperation of said pins with 90 said article.

3. A measuring instrument comprising a support, members having recesses to coöperate with an article to be gaged for maintaining said members in position thereon, blocks 95 having adjustable pins to coöperate with said article, and means to maintain said pins and members in spaced gaged relation.

4. A measuring instrument comprising a 100 support, members having recesses to coöperate with an article to be gaged, for maintaining said members in position thereon, blocks having adjustable pins to coöperate with said article and gage blocks interposed 105 between said pins, and means to maintain said members and blocks in spaced gaged relation.

5. A measuring instrument comprising a support having an interior space, members 110 having portions adapted to fit in said space and provided with shoulders to coöperate with said support, said members having recesses to coöperate with an article to be gaged to maintain the members in alinement thereon, blocks having pins to coöperate with said article, and means to maintain said pins in spaced gaged relation. 115

6. A measuring instrument comprising a support having an interior space, members 120 having portions adapted to fit in said space and provided with shoulders to coöperate with said support, said members having recesses to coöperate with an article to be gaged to maintain the members in alinement 125 thereon, blocks having pins to coöperate with said article, gage blocks adapted to fit in said space to maintain said pins in spaced relation, and means to retain said members and blocks in said relation. 130

7. A measuring instrument comprising a support having an interior space, members having reduced portions in said space and provided with recesses to coöperate with an article to be gaged, blocks in said space provided with adjustable pins, gage blocks in said space adapted to be interposed be-

tween said pins, and means to maintain said members and blocks with said pins in spaced gaged relation.

Signed at New York, in the county of New York and State of New York this 13th day of March, A. D. 1919.

HERBERT G. PECK.
